United States Patent [19]

Hill

[11] Patent Number: Des. 290,930

[45] Date of Patent: ** Jul. 21, 1987

[54] CIRCUIT BOARD SUPPORT

[75] Inventor: Royce W. Hill, Flippin, Ark.

[73] Assignee: Micro Plastics, Inc., Flippin, Ark.

[**] Term: 14 Years

[21] Appl. No.: 734,154

[22] Filed: May 15, 1985

[52] U.S. Cl. .... D8/354; 174/138 D

[58] Field of Search .... D8/354, 349; D13/24, D13/99; 174/138 D; 24/305

CLAIM

The ornamental design for a circuit board support, as shown and described.

DESCRIPTION

FIG. 1 is a perspective view of a circuit board support showing my new design;

FIG. 2 is a side elevational view thereof, the side opposite being a mirror image;

FIG. 3 is a front elevational view thereof, the rear view being a mirror image;

FIGS. 4 and 5 are respectively top and bottom plan views thereof;

FIG. 6 is a sectional view taken along line 6—6 of FIG. 2 in the direction of arrows; and

FIG. 7 is a sectional view taken along line 7—7 of FIG. 3 in the direction of arrows.

FIG. 1

FIG. 2

FIG. 3

FIG. 4

FIG. 5

FIG. 6

FIG. 7
